Design No. 18,396, dated June 19, 1888.

UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A TEA-GOWN.

SPECIFICATION forming part of Design No. 18,396, dated June 19, 1888.

Application filed May 18, 1888. Serial No. 274,316. Term of patent 3½ years.

To all whom it may concern:

Be it known that I, ELLEN MORAN, of the city, county, and State of New York, have invented and produced a new and original Design for a Pattern of a Lady's Tea-Gown; and I do hereby declare that the engraved prints accompanying this specification convey to any one accustomed to using paper patterns a clear understanding of how a garment made up by the pattern will appear.

The design shows narrow fronts opening from the shoulders down over a full vest that displays a V of smocking at the top, a girdle of smocking below the waist-line, and smocked sash-ties falling low upon the vest; a close-fit-

ting back that exhibits underfolded plaits below the waist-line of its middle three seams; a standing collar, and coat-sleeves that display a long puff at the inside of the arm, having a deep smocking at the wrist.

20

What I claim as my invention, and desire to secure by Letters Patent, is—

The design for a lady's tea-gown, as shown in the engraved prints accompanying this specification.

ELLEN MORAN.
